UNITED STATES PATENT OFFICE.

FRANK C. LEFLER, OF ROCHESTER, NEW YORK.

GUN-LOCK.

1,219,964.

Specification of Letters Patent. Patented Mar. 20, 1917.

Application filed November 18, 1914. Serial No. 872,728.

To all whom it may concern:

Be it known that I, FRANK C. LEFLER, of Rochester, in the county of Monroe and State of New York, have invented a new 5 and useful Improvement in Gun-Locks, which improvement is fully set forth in the following specification and shown in the accompanying drawings.

The present invention relates to gun locks 10 and more particularly to that type in which a single trigger is adapted to effect the operation of a plurality of hammers, an object of this invention being to provide a construction in which a very small trigger action is present, the trigger moving substantially the same distance for the several firing actions. Another object of the invention is to provide a stop action for the first actuation of the trigger, which will be released upon the recoil of the gun, due to the unconscious release of the trigger by the operator on such recoil. Still another object of the invention is to provide a locking device which is operated upon the rebound 25 of the gun and after the stop action has become ineffective. A still further object of the invention is to provide a gun lock which employs a minimum number of parts for effecting the different functions of the gun.

To these and other ends, the invention consists in certain parts and combinations of parts all of which will be hereinafter described, the novel features being pointed out in the appended claims.

In the drawings:

Figure 1 is a detail view of a portion of a gun embodying the present improvements and showing the gun lock set for firing the two barrels;

Fig. 2 is a view similar to Fig. 1 showing the position of the parts after the trigger has been pulled and before recoil;

Fig. 3 is a view similar to Figs. 1 and 2 showing the positions of the parts during 45 the rebound of the gun;

Fig. 4 is a view similar to Figs. 1, 2 and 3 showing the positions of the parts after the firing of the second barrel;

Fig. 5 is a view of the opposite side of the 50 gun lock with the parts in the position shown in Fig. 4;

Fig. 6 is a section on the line $a-a$, Fig. 4; Fig. 7 is a section on the line $b-b$, Fig. 6; Fig. 8 is a perspective view of the sear lifter;

Fig. 9 is a perspective view of a controller

for determining which sear is to be actuated first;

Fig. 10 is a perspective view of the setting device for the controller; and

Fig. 11 is a detail of the trigger spring.

Referring more particularly to the drawings, 1 indicates the barrels, of which there are two in this instance, rigidly secured together in the usual manner and having pivoted at 4 the rearwardly tilting breach frame 5 which carries the usual hammers (not shown) controlled by the sears 6 in the usual manner pivoted at 7 to the breach frame 5.

For controlling these sears, a single trigger 8 is employed pivoted at 9 to a frame piece which extends upwardly at 10 from the plate 11 at a point between the sears 6, thence rearwardly at 12, again upwardly at 13, again rearwardly at 14 and finally downwardly at 15 to the plate 11, being held to said plate at both ends by screws 16. The trigger preferably does not directly engage with the sears but an intermediate member 17 is employed in the form of a sear lifting plate which is pivoted to turn about the axis 9 of the trigger on the upwardly-extending portion 10 of the frame. This lifting plate overlies the trigger so that it may be moved upwardly by the trigger to actuate the sears 6.

Arranged on the lifting plate is the controller for determining which of the sears is to be first actuated. This controller, in this instance, is in the form of a plate 18 formed with notches 19 and 20 in opposite sides thereof and guided by a pin 21 for a sliding movement upon the lifting plate so that either one of the notches 19 and 20 may lie below the inwardly-turned ends 22 and 23 of the sears 6 while, to the forward side of the notch 19 and to the rearward side of the notch 20, shoulders or faces 24 and 25 respectively are provided for respectively engaging the inturned ends 22 and 23 of the sears 6, the arrangement being such that, when the end 22 of one sear lies over the notch 19, the end 23 of the other sear will lie over the shoulder 25, and vice versa. By this construction, the end of the sear which lies over the shoulder 24 or 25 will be the first one to be actuated while the end of the sear which lies over the notch 19 or 20 will be the last to be actuated.

The movement of the controller 18 may be effected by an actuator in the form of a

bar 26 which lies below the lifting plate. This bar has a finger piece 27 extending to the exterior of the gun to one side of the trigger and it carries an upwardly-extending pin 28 which extends through a slot 29 in the lifting plate and engages within an opening 30 in the controller, so that a movement of the finger piece 27 is transmitted to the controller 18. The actuator preferably partakes of the up and down movements of the lifting plate, and, to this end, is guided on the latter by means of a pin 31 extending laterally from a rearward extension 32 on the lifting plate and operating within a slightly V-shaped slot 33 in a rearward extension on the actuator 26, this slot being formed as shown for holding the actuator in its two positions, there being a slight resiliency in the actuator 26 to permit the actuator to move on the pin 31 from one end of the notch to the other.

In order that both sears will not be simultaneously operated upon a single movement of the trigger in an upward direction, a stop action of novel construction is employed. This stop action preferably embodies a detent 35 bifurcated at its lower end and straddling the rearward extension 32 of the lifter, being pivoted on said lifter at 36 so as to extend upwardly therefrom. Its upper end is adapted to coöperate with a stop shoulder 37 formed on the rear face of the upwardly-extending portion 13 of the frame piece and parallel with the longitudinal axis of the gun. A leaf spring 38 carried by the frame piece normally acts on the detent 35 to hold the latter out of a path where said detent will engage with the shoulder 37. Upon the upward movement of the trigger, a rearward extension 39 on said trigger coöperates with an arm 40 on the detent 35 and swings the upper end of the detent 35 forwardly to compress the spring 38 so that, on the first firing of the gun, the upper end of the detent 35 will engage with the shoulder 37 and stop the trigger and lifter before the second sear is actuated. Upon the recoil of the gun, the user unconsciously releases the trigger and the upper end of the detent then is moved automatically out of engagement with the shoulder 37 by the spring 38 and the sear lifter moves into operative relation with the other sear due to the provision of a spring 38 which acts on the trigger 8.

To the end that the second barrel will not be fired upon the rebound of the gun, due to the reengagement of the finger of the operator with the trigger by such rebound, a rebound actuated lock is employed which enters into operation during the rebound and after the primary stop action has become inoperative during the recoil. This rebound-operated lock is preferably in the form of a block 41 bifurcated at its lower end and straddling the rearward extension 32 of the

lifter, being pivoted at 42 to said lifter in rear of the detent 35 to project upwardly from the lifter. The upper end of this block is curved at 43 with the pivot 42 as the center, while the forward face of the block is provided with an extension 44 to coöperate with the rear face of the frame portion 13 above the shoulder 37, this coöperation being maintained under normal conditions by a spring 45. As before stated, upon the recoil the detent 35 passes out of engagement with the shoulder 37 so that, upon the rebound, the weighted block 41 may move rearwardly in order that its curved portion 43 may coöperate with the curved abutment 46 on the frame portion 15. On this rebound, the finger again unconsciously presses on the trigger so that the curved face 43 is maintained in engagement with the curved abutment 46 and holds the trigger against upward movement until pressure on the trigger is removed, when the parts assume the positions for the firing of the second barrel which is effected by an upward pressure on the trigger causing the other sear to be lifted by engagement with the upper face of the lifting plate 18, due to the lateral or in-turned extension on the sear operating in one of the notches 19 or 20 of the controller.

The operation of the invention will, it is thought, be understood from the foregoing description but it may be summarized as follows:

Either barrel may be fired first, this being accomplished by shifting the finger piece 27 to present either of the inwardly-turned portions 22 or 23 of the sears to its respective notch 19 or 20 in the controller plate, and the other to its respective shoulder 24 or 25. When the trigger is pulled, after setting the gun, the shoulder 24 or 25 will elevate its respective sear permitting the other sear to remain inactive by entering the notch 19 or 20. The trigger can only rise until the stop detent 35 engages the abutment or shoulder 37. At this time, the recoil takes place, removing the detent 35 from the shoulder 37 automatically due to the unconscious release of the trigger on recoil. On the rebound of the gun, the rebound operated block 41 moves rearwardly and, at the same time, pressure is unconsciously applied to the trigger 8, thus carrying the curved shoulder 43 of the block into engagement with the curved shoulder 46, where it is held until the trigger is again released when the gun is ready for the second firing, the latter being effected by the engagement of the second sear with the upper face of the lifting plate 17 through one of the notches 19 or 20.

A gunlock constructed in accordance with this invention has a shorter or less trigger action due to the stop action being released on the recoil and the trigger being held substantially in the position which it reached

at the end of the first firing thereby making the trigger move substantially the same distance for both firing actions. The rebound-operated block swings rearwardly to act 5 after the stop action and acts notwithstanding that the stop action has been released.

What I claim as my invention and desire to secure by Letters Patent is:

1. A double barrel gun having in combination, two sears, one for each barrel, a single trigger for successively operating the sears, a spring acting on the trigger to hold it against return movement after operating one of the sears, and a stop action for the 15 first operation of the trigger, releasing the latter when pressure is relieved on the trigger during the rearward movement of the gun due to recoil.

2. A double-barrel gun having, in combination, two sears, one for each barrel, a trigger, a lifter operated by the trigger to operate the sears successively, a shoulder on the frame of the gun, a detent movably mounted on the lifter and operated by the 25 trigger to engage said shoulder when the trigger is pulled to fire the first barrel, a spring for moving said detent out of engagement with the shoulder when pressure is relieved on the trigger during the rearward movement of the gun due to recoil and a spring acting to prevent the return movement of the trigger when pressure is relieved thereon.

3. A double barrel gun having, in combination, two sears, one for each barrel, a trigger, a lifter operated by the trigger and operating the sears successively, a pivoted detent on the lifter, engaged by the trigger, a straight shoulder on the frame of the gun 40 adapted to be engaged by the detent and extending in a line parallel with the longitudinal axis of the gun, a spring for moving said detent out of engagement with the shoulder when pressure is relieved on the trigger during recoil, and a spring acting on said trigger to prevent the return of the trigger when pressure is relieved thereon.

4. A double barrel gun having, in combination, two sears, a single trigger for successively operating the sears, a stop action for the first action of the trigger, releasing

the latter when pressure is relieved on said trigger during the rearward movement of the gun due to recoil, a shoulder on the frame of the gun, a stop movable rearwardly by the rebound of the gun to engage such shoulder to prevent firing by pressure of the trigger during rebound, and a spring for moving said stop forwardly out of stopping position after rebound. 55

5. A double barrel gun having, in combination, two sears, operating mechanism for successively operating the sears and embodying a single trigger, a stop action controlled by the trigger, a fixed shoulder on the barrel, a detent movable rearwardly to engage the fixed shoulder during the forward movement of the gun due to the rebound to prevent firing by pressure on the trigger during rebound. 65

6. A double barrel gun having, in combination, two sears, operating mechanism for successively operating the sears and embodying a single trigger, a stop action controlled by the trigger and movable out of 70 stopping position on the rearward movement of the gun due to recoil, a curved shoulder on the frame, and a pivoted rebound actuated stop movable rearwardly on the operating mechanism to engage said 75 shoulder.

7. A double barrel gun having, in combination, two sears, a single lifting plate for both sears, a trigger for moving the plate, a shoulder, a detent mounted on the plate 85 and shifted by the trigger to a position to engage the shoulder when the trigger is moved to fire the first barrel, a spring for moving the detent out of engagement with its shoulder during the rearward movement 90 of the gun due to recoil, a fixed shoulder on the frame of the gun, a rebound actuated stop mounted on the lifting plate and movable rearwardly to engage the shoulder on the forward movement of the gun due to 95 rebound, and a spring for moving said stop out of engagement with its shoulder after the forward rebound movement of the gun.
